SAFETY-SWITCHES FOR MAKING AND BREAKING ELECTRIC CIRCUITS William C. Wilson and Alva J. Bishop, Jr.,
Zanesville, Ohio

Application July 23, 1954, Serial No. 445,378

4 Claims. (Cl. 200—165)

This invention relates to improvements in safety-switches for making and breaking electric circuits, such as the battery circuits in automobiles, and also circuits in buildings and the like.

One of the objects of our invention is to produce a safety-switch for use primarily in the ground circuit of an automobile battery but which may be employed for opening and closing an electric circuit generally, occupies a minimum amount of space or room, and which will comprise conical switch members mounted to produce a simple, rugged construction that will enable ready, quick and easy assembly of the parts into a highly efficient switch which will avoid mechanical failure, may be operated with great facility and which will be operable, upon a making operation, to provide immediately an increased area of contact and upon a disconnecting or opening operation will produce an immediate and complete breaking of the circuit.

Another object of our invention is to provide a switch for connecting and disconnecting the ground circuit from the battery circuit of an automobile which may be operated by the use of a controlling element placed in a convenient location for an operator of a vehicle to permit instantaneous operation generally and also, in case of a short circuit in wiring causing fire, the operator of the vehicle can pull the control cord and disconnect all the current from the battery.

Another object of our invention is to provide a switch of the type specified which may be readily and quickly operated, and which will not only stop a fire in a vehicle caused by defective wiring but will enable the prevention of a fire in any vehicle by turning the control to "off" position when the vehicle is not in use such as when a car is parked in a garage under a house, or close to a house, tractors and farm machinery, parked in barns, house-boats, etc.

Another object of our invention is to provide a switch construction in which conical switch members are so arranged in relation to each other and also aligned and guided in their relative movements to cause the circuit upon a making operation to be instantly and completely closed without any drag, and in a breaking operation to cause such conical switch members to be instantly and positively separated to completely and instantly break the circuit.

Another object of our invention is to provide a cone switch in which one of the conical switch members will comprise a fixedly-supported, inwardly-projecting cone which is completely insulated from other parts, and is combined with a movable member embodying a conical depression of identical magnitude to the fixed projecting cone.

Another object of our invention is to provide means for movably mounting said movable conical switch member in relation to said fixed conical members to produce precise registration of the two members.

Another object of our invention is to utilize a compact

2

switch having a supporting structure enclosing the movable parts and comprising a rugged, cylindrical casing closed at one end by a fixed transversely-disposed disc-shaped top, the upper surface of which is adapted to be utilized as a cam-mounting surface or operating table, while the body of said disc-shaped top is employed as a fixed support for one end of a plurality and preferably of three guiding elements or posts which surround the axis of the casing and serve to mount, align and guide the movable conical switch-member in its movements into engagement and disengagement with the fixed projecting cam element.

Another object of our invention is in a device of the character specified to provide for operative movements of the movable conical switch member by springs and a cam having a mounting stem axially connected with and operable to instantly move the movable conical switch member into or out of complete connection or disconnection with the fixed conical switch member.

Another object of our invention is to utilize at the bottom end of the casing an axially-positioned connecting element to connect our fixed conical switch member to a battery terminal in a circuit and to utilize for connection of the switch to a ground terminal a connecting element arranged transversely at substantially right angles to the connecting element for the battery terminal and movable in a longitudinally disposed slot in the side wall of the cylindrical casing.

Still another object of our invention is in a device of the character specified to utilize a plurality of springs on the guiding posts for the purpose of automatically connecting the conical switch members upon the movement of a cam by its operating mechanism.

Another object of our invention is to utilize a simple cam construction in which the cam comprises a simple metallic plate having at one end a pointed rectangular cam surface that provides for a cam movement by positioning an axle member to one side of the axis of the pointed cam element, and thus, by a tilting of the cam enabling a lifting of the connecting stem above the top of the cam or cam-operating table and a consequent disconnection of the conical switch members.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:

Fig. 1 is a view in side elevation of a switch of our connection connected up to the battery and ground circuit of an automobile, the parts being shown in open position;

Fig. 2 is a top plan view of the switch shown in Fig. 1;

Fig. 3 is a center, longitudinal section showing the cam in operative position to move the parts to produce a breaking of the circuit;

Fig. 4 is a similar section showing the cam in an operative position to close the circuit.

Referring now to these drawings which illustrate a preferred embodiment of our invention, 10 indicates a rugged and strong cylindrical casing closed at its upper end with an integral disc or end plate 13 to provide an enclosing casing for the working parts of our switch. The integral disc 13 provides on its outer surface a cam-supporting table and the body of said disc provides a support for one end of each of a series of guide rods 14 as hereinafter specified.

The casing 10 in the embodiment shown is provided intermediate its ends with a base 11 adapted to permit

mounting of the switch on a fire wall 12 of an automobile, said base 11 having flanges adapted to lie flat against and to be connected to said fire wall 12.

In the embodiment shown, the integral end plate or disc 13 serves as above indicated as a support for the upper or inner ends 14^a of a series of three rods or posts 14 which are positioned to surround the axis of the cylinder. Each rod or post is screw-threaded and firmly supported and held in place at its upper end within the casing by nuts 15. The guide rods 14 have their opposite ends fixedly mounted and supported by screws and nuts 14^a in a thick, sturdy insulating ring 16 which closely fits the lower rim portion of our cylindrical casing, and thus firmly held in place within said rim portion by said rods or posts and has a thick outer edge that abuts the inner surface of the casting to assist in positioning thereof. The lower ends of said posts or rods 14 are completely surrounded by insulating material and are thus insulated from a heavy fixed conical switch member 17 which is supported in said ring of insulation material and formed of a suitable current-transmitting material, and has its cone-shaped head portion 17^a extending axially inwardly into the casing, while its base portion 17^b has interengaging flanges fitting into and held within said ring of insulating material.

Said fixed conical switch member 17 has axially projecting outwardly from the base thereof a heavy screw-threaded connecting element 18 provided with suitable nuts 19 for the purpose of securely connecting to said fixed conical switch member a terminal of an automobile battery cable 20 which leads to a battery or batteries, not shown.

Slidably mounted within the casing 10 on the rods 14 and movable into and out of contact with said cone-shaped head portion of said fixed conical switch member 17 is a movable conical switch member 21 having a conical socket 22 adapted to match and closely fit the cone-shaped head 17^a of the fixed conical switch member 17.

The socketed conical switch member 21 has projecting from its side circumferential surface a heavy screw-threaded cable-securing connecting element 23 which is also provided with nuts 24 for the purpose of securely attaching thereto a ground cable 25, the opposite end of which will in the conventional manner be connected to the ground or chassis of an automobile. As shown, the connecting element 23 carries a ferrule 23^a which extends outwardly from a suitable position on the circumference of the socket member 21 and encloses the connecting element 23. Said ferrule 23^a and screw 23 are thus adapted to move or slidably reciprocate within a vertical guide slot 10^b in the cylindrical side wall of the casing 10.

In Fig. 3 the movable conical socketed switch member 21 and the fixed projecting conical member 17 are shown in separated or circuit-breaking open position while in Fig. 4 the movable conical socketed member 21 is shown in closed circuit-making position. Movement of the two members is effected as follows:

The movable socketed switch member 21 has projecting axially upwardly therefrom a screw-threaded bearing element 21^a having at its upper end a pivot 26 about which an operating cam element 27 composed of a narrow flat plate having a pointed lower end formed between its side edges by a rectangular surface 27^a having its pointed end arranged centrally of the element 27 and about which the said element is adapted to be rocked. The said pointed rectangular surface is converted into a cam surface by positioning in said plate to one side of a centrally-located line extending to the point 27^b of said pointed rectangular surface the pivot bearing 26^a for the pivot 26 and utilizing the flat table top 10^a as the movement-limiting element for engagement with the cam surfaces at opposite sides of the point and pivot thereof. The cam surface so formed is thus adapted

to be moved about the pivot 26^a for the purpose in one tilted position of raising the movable socketed switch member 21 in relation to the casing 10 to break the circuit and in its opposite tilted position permitting said switch member 21 to be lowered into circuit-making position with the switch member 17.

In Fig. 3 the cam member 27 has been moved about its pivot to an inclined position which causes engagement with the table top 10^a of that portion of the cam surface which is more remote from the pivot, thus producing a lifting of said member 21 and causing the wall of the socket 22 of the switch member 21 to be moved upwardly out of contact with the conical surface 17^a of the switch member 17.

In Fig. 4, the cam member 27 has been swung about its pivot to an inclined position opposite to that shown in Fig. 3 in which the cam surface that is closer to the pivot engages with the table top, thus permitting a lowering of said switch member 21 into a position in which

20 the wall of the socket 22 of said switch member will have contact with the conical surface 17^a of switch member 17. In order to positively move said socketed member into contact with said projecting conical member 17, we provide three springs 14^a which are positioned to surround the axes of the said conical switch members and are preferably mounted on the three posts 14.

Suitable means is provided for manually swinging the operating cam member 27 about its pivot to the positions 30 above specified, and, as illustrated, we have for this purpose shown a rod 28 connected at one end to said cam 27 and extending through a tube 29. The rod 28 passes through automobile walls and has a portion 28^a connected to a handle 30 on the dash-board of a vehicle.

35 Obviously, in operation, when the operating element 27 is manually moved to the inclined position shown in Fig. 4 the switch members 21 will be automatically moved by expansion of the springs 14^a into close contact with the member 17 and when said member 27 is manually 40 swung into the position shown in Fig. 3 the action of the cam will compress the springs and cause a separating movement of the switch members.

It will be understood that by the utilization of the conical switch member 17 with its conical surface 17^a in axial alignment with the conical socket 22 in the switch member 21, a cool contact mechanism will be produced for the purposes specified in the object clauses hereinabove specified.

It will also be understood that the use of conical surfaces provides much larger contact surfaces than conventional switches and these two conical surfaces when aligned and moved into complete contact with each other by the use of a series of guide rods that surround the axes of the two switch members provide a switch construction that will possess the many advantages hereinabove specified.

Having described our invention, we claim:

1. A safety switch for making and breaking electric circuits comprising a pair of mating conical switch members composed of current-transmitting material, said pair composed of a fixed projecting cone provided with a continuous conical surface and a movable switch member of greater diameter and having at its axis a matching conical socket provided with a similar continuous switch contact area adapted to fit over and produce conical contacting surfaces of large diametric dimensions and wide cylindrical body portions surrounding said socket, means for supporting said projecting-cone member in fixed position comprising an insulating disc, means for mounting the movable member to move axially into and out of electrical-contacting engagement with its mate, guiding means positioned in said wide body portion at a plurality of points surrounding the socket in said movable member and extending parallel to the axis thereof for aligning the 70 same to simultaneously produce a complete contact of

the switch contact areas thereof with the contact areas of its mate, means for individually connecting said switch members in an electric circuit, operating means for moving said movable switch member axially into circuit-breaking position, and means operable upon the release of said operating means for automatically moving said members to circuit-making position.

2. A safety switch for making and breaking electric circuits comprising a pair of mating conical switch members composed of current-transmitting material, said pair composed of a fixed switch member provided with a continuous conical surface and a movable switch member having at its axis a matching conical socket and provided with a similar continuous switch contact area adapted to fit over and produce conical contacting surfaces of large diametric dimensions, means for supporting one of said cone members in fixed position, means for mounting the movable member to move axially into and out of electrical-contacting engagement with its mate, guiding means surrounding the conical portion of said movable member and extending parallel to the axis thereof for aligning the same to simultaneously produce a complete contact of the switch contact areas thereof with the contact areas of its mate, means for individually connecting said switch members in an electric circuit, operating means comprising cam mechanism connected axially to the movable member of said pair of switch members and having a pair of cams, one of which is a circuit-breaking cam operable to move and retain the movable switch member into circuit breaking position, and the other cam member of said pair of cams comprises a circuit-making cam operable upon the release of said circuit-breaking cam to automatically move said switch member to circuit-making position and to retain the same therein.

3. A safety switch for making and breaking electric circuits comprising a support composed of a cylindrical casing having at one end an integral disc closing said end and serving as a cam-supporting table, a pair of mating conical switch members mounted within said casing and composed of current-transmitting material, one member of said pair comprising a fixed switch member provided with a continuous conical surface and the other switch member comprising a movable disc having at its axis a matching conical socket and provided with a similar continuous switch contact area adapted to fit over and produce conical contacting surfaces of large diametric dimensions, means at the opposite end of said casing comprising a flat insulating disc and contacting and insulating the fixed member and for supporting said fixed member in fixed position, means for mounting the other member within the body of said casing to move into and out of engagement with its mate, guiding means for aligning the same to simultaneously produce a complete contact of the switch contact areas thereof with the contact areas of its mate, means for individually connecting said members in an electric circuit, and operating means for mov-

ing said movable switch member comprising cam mechanism mounted on said cam-supporting table and connected axially to the movable member of said pair of switch members, said cam-mechanism comprising a pair of cams operable by movement in opposite directions, one of which cams is a circuit-breaking element operable to move and retain the movable switch member into circuit-breaking position, and the other cam member of said pair of cams comprises a circuit-making cam operable upon the release of said circuit-breaking cam to automatically move said switch member to circuit making position and to retain the same therein.

4. A safety switch for making and breaking electric circuits comprising a support composed of a cylindrical casing having at one end an integral disc closing said end and serving as a cam-supporting table, a pair of mating conical switch members mounted within said casing and composed of current-transmitting material, one member of said pair comprising a fixed switch member provided with a continuous conical surface and the other switch member comprising a movable disc having at its axis a matching conical socket and provided with a similar continuous switch contact area adapted to fit over and produce conical contacting surfaces of large diametric dimensions, means at the opposite end of said casing comprising a flat insulating disc and contacting and insulating the fixed member and for supporting said fixed member in fixed position, means for mounting the other member within the body of said casing to move into and out of engagement with its mate, guiding means for aligning the same to simultaneously produce a complete contact of the switch contact areas thereof with the contact areas of its mate, means for individually connecting said members in an electric circuit, and operating means for moving said movable switch member embodying cam mechanism connected axially to the movable member of said pair of switch members and comprising a single pointed cam element having an eccentric connection with the axis of said movable member to provide a pair of cams operable by movement in opposite directions of the cam element about its point and one of which pair of cams is a circuit-breaking cam operable to move the movable member into circuit-breaking position and to retain the same therein, and the other member of said pair of cams comprises a circuit-making cam operable upon the release of said circuit-breaking cam to automatically move said members to circuit-making position and to retain the same therein.
